UNITED STATES PATENT OFFICE

120,165

DESIGN FOR A KNITTED FABRIC

Lew E. Braverman, New York, N. Y.

Application February 7, 1940, Serial No. 90,120
Term of patent 3½ years

To all whom it may concern:

Be it known that I, Lew E. Braverman, a citizen of the United States, residing in New York city, in the county of New York and State of New York, have invented a new, original, and ornamental Design for a Knitted Fabric, of which the following is a specification, reference being had to the accompanying drawing, forming part thereof.

The figure is a plan view of a knitted fabric showing my design.

I claim:

The ornamental design for a knitted fabric, substantially as shown.

LEW E. BRAVERMAN.
